UNITED STATES PATENT OFFICE.

GEORGE LAWSON GREEN, OF NEWARK, ARKANSAS, ASSIGNOR TO CHARLES G. HENRY,
OF NEWPORT, ARKANSAS.

TOOL-HOLDER.

1,165,500.

Specification of Letters Patent. Patented Dec. 28, 1915.

Application filed April 27, 1915. Serial No. 24,329.

To all whom it may concern:

Be it known that I, GEORGE LAWSON GREEN, a citizen of the United States, residing at Newark, in the county of Independence and State of Arkansas, have invented 5 a new and useful Tool-Holder, of which the following is a specification.

The present invention appertains to tool holders, and aims to provide a novel and improved means for adjustably attaching the shank of a tool to the end of a handle or standard, whereby the tool may be readily attached to and detached from the handle or standard, and may be set at various positions relative to the handle or standard.

It is also within the scope of the invention to provide a device of the nature indicated which is extremely simple, compact and inexpensive in construction, and which 20 is thoroughly practical and efficient in use.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a side elevation of the improved tool holder. Fig. 2 is an enlarged sectional detail taken on the line 2—2 of Fig. 3, and illustrating the shank of the tool in the same position that it occupies in Fig. 1. Fig. 3 is an enlarged sectional detail taken on the line 3—3 of Fig. 1 and illustrating the shank in another position.

In carrying out the invention, there is provided a sleeve or ferrule 1 adapted to be slipped over the end of the standard or handle 2 and to be secured thereon in any suitable manner. The part 2 is to be taken as an arbitrary one, since it may be the handle of a hand implement, or the standard of a cultivator, it being understood that the 50 sleeve 1 may be attached to various objects to which the tool or implement is to be attached.

The sleeve 1 is provided at its free end with a hollow cube-like head 3, which is 55 provided at opposite sides with rectangular

openings 4, the said sides being flush with the respective sides of the sleeve 1. The wall or partition 5 of the casting which is disposed between the body of the sleeve 1 and the interior of the head 3, is provided with a rectangular opening 6, and the opposite or end wall of the head 3 is provided with a similar opening 7. The openings 4 are in alinement, and this is also true of the openings 6 and 7, and said openings are of 60 smaller area than the respective walls of the head 3. A set screw 8 is threaded through one of the other side walls of the head 3 which is flush with the sleeve 1.

The openings of the head 3 are adapted 70 to receive the shank 9 of a tool, blade or implement 10, which may be of any suitable construction, the shank 9 being of square or rectangular cross section and the end portion of the shank 9 being provided at one 75 side with a pair of spaced transverse notches 11.

When the shank 9 is inserted laterally through the openings 4, the shank 9 will be arranged at right angles with respect to the 80 sleeve 1 and member 2, and by moving the shank 9 longitudinally of the sleeve 1, the notches 11 will be engaged by the relatively wide portions 12 of those sides of the heads 3 having the openings 4, and the set screw 85 8 may then be tightened to clamp the shank 9 in place. The shank 9 is thus rigidly secured to the sleeve 1. When the set screw 8 is loosened, the shank 9 may be readily withdrawn, and the shank 9 may be fastened to 90 the sleeve 1 in alinement therewith. When it is desired to have the shank 9 project longitudinally from the sleeve 1, the end of the shank is inserted through the openings 7 and 6 of the head 3, as seen in Fig. 3, whereby 95 the relatively wide portions 13 of the respective walls of the head 3 will engage the notches 11 of the shank when the set screw 8 is tightened, and this will hold the shank 9 firmly in place.

With the present device, it is thus possible to readily apply and remove the tool, and to hold the tool at various positions relative to the handle or standard 2, in order that the holder will be serviceable and convenient in 105 use.

Since the various holders may be employed for various purposes as will be evident to those familiar in the art, it is not deemed necessary to illustrate or describe a specific 110

use of the holder, since the application of the holder for various uses will be obvious.

Having thus described the invention, what is claimed as new is:

- 5 The combination with a tool holder comprising a sleeve having a hollow cube-like head at one end, opposite side walls of said head having alining openings, the end wall and opposite wall of the head having alining 10 openings, said openings being of smaller area than the respective walls of the head, and a set screw threaded through one of

the other walls of the head, of a shank insertible through either the first mentioned or second mentioned openings and having notches for the engagement of the respective walls of said head.

In testimony that I claim the foregoing as my own, I have hereto affixed my signature in the presence of two witnesses.

GEORGE LAWSON GREEN.
